UNITED STATES PATENT OFFICE

170,094

COMBINATION SINK AND CABINET UNIT

Edward W. Schmitt, Cincinnati, Ohio

Application February 13, 1953, Serial No. 23,600

Term of patent 7 years

(Cl. D33—19)

To all whom it may concern:

Be it known that I, Edward W. Schmitt, a citizen of the United States of America, residing at 28 West Court Street, Cincinnati, Ohio, have invented a new, original, and ornamental Design for a Combination Sink and Cabinet Unit, of which the following is a specification, reference being had to the accompanying drawing, forming a part hereof.

The single figure is a perspective view of a combination sink and cabinet unit showing my new design.

I claim:

The ornamental design for a combination sink and cabinet unit, as shown.

EDWARD W. SCHMITT.
